UNITED STATES PATENT OFFICE.

JOHN A. WILLIAMS, OF AURORA, MISSOURI, ASSIGNOR OF ONE-HALF TO CHARLES G. THOMPSON, OF AURORA, MISSOURI.

SYSTEM OF HOT-WATER DISTRIBUTION.

1,173,759.

Specification of Letters Patent. Patented Feb. 29, 1916.

Application filed December 9, 1914. Serial No. 878,246.

To all whom it may concern:

Be it known that I, JOHN A. WILLIAMS, a citizen of the United States, and a resident of Aurora, in the county of Lawrence and State of Missouri, have made certain new and useful Improvements in Systems of Hot-Water Distribution, of which the following is a specification.

This invention relates to an improvement in systems of hot water distribution, and one of the principal objects of the invention is to provide a system of hot water distribution in which the usual hot water tank is employed, whereby hot water may be drawn when desired directly from the heating coil without interfering with the continued circulation of the water through the tank and coils.

A further object of the invention contemplates the provision of an auxiliary pipe connecting the fixture supply pipe with the return pipe from the coil at a point in the latter between the coil and tank, and also the provision of suitable valves through the manipulation of which water may be drawn in the usual way from the supply tank, or may be drawn as it leaves the heating coils.

With these and other objects in view which will become apparent as the description proceeds, the invention resides in the construction, combination and arrangement of parts hereinafter more fully described and claimed, and illustrated in the accompanying drawing in which the figure illustrates an elevational view of a hot water system incorporating my invention.

In the drawing, a tank or reservoir is indicated at 5, and a heater is indicated at 6. The tank is supplied with cold water through the feed pipe 7. A coil 8 in the heater is connected with the lower portion of tank 5 by pipe 9 and is also connected with the tank through the medium of a return pipe 10. The arrangement of the tank and coil and connecting pipes is an ordinary one, and provides for the circulation of the water from the tank through pipe 9 into the coil where it is heated and back to the tank through the return pipe 10, the hot water being discharged from said pipe 10 into the tank above a point at which the feed pipe 7 discharges into said tank so that the hot water gathers in the upper portion of the tank, as is usual.

The water fixtures include a tub and basin 11 and 12, respectively, as indicated in the drawing and are supplied by the pipe 13 which connects with the discharge pipe 14 of tank 5 in the usual manner. Thus, in the ordinary arrangement hot water from the tank is supplied to fixtures through the pipes 14 and 13.

I provide an auxiliary pipe 15 connected at one end to the fixtures supply pipe at point 16, and connected at its opposite and upper end to return pipe 10 at the point 17. A control valve 18 is provided in pipe 15 near pipe 10, and a control valve 19 is provided in pipe 14. Between the point of connection of pipes 10 and 15 and tank 5, a check valve 20 is provided. This valve is adapted to allow passage of water through pipe 10 only toward the tank.

One of the principal advantages of my invention resides in the fact that hot water may be obtained in a very short time after the heater has been lighted and without necessitating the filling of tank 5 with hot water before it may be supplied to the fixtures. This may be done by closing valve 19 which shuts off the flow through pipe 14, and opening valve 18 so as to allow flow through pipe 15. Water may then be drawn directly from the coil 8 to the fixtures 11 or 12 or from a faucet indicated at 21, so that a supply of hot water may be obtained in a very short time after the heater has been lighted. Should the water in the tank become thoroughly heated, when the need for hot water arises, control valve 19 is opened and valve 18 is closed, thus allowing the flow through pipe 14 and cutting off the flow through pipe 15.

It will be noted that in the first instance when the hot water is drawn from the return pipe directly after it leaves coil 8, the continued circulation of the water from the tank to the coil and back to the tank is not interfered with, being only interrupted during the time when the valves at the fixtures are open.

Although I have described the preferred embodiment of my invention, I may desire to make such changes in the construction, combination and arrangement of parts thereof as do not depart from the spirit of the invention and the scope of the appended claims.

12
I claim:—

1. In a system of the class described, the combination with a tank having a feed pipe and a discharge pipe leading to fixtures, 5 and a coil having an inlet connection with the lower portion of the tank and having a return pipe leading from the coil to the tank, of an auxiliary pipe connected at one end to the tank discharge pipe and at its 10 opposite end to said return pipe, a control valve in the tank discharge pipe, a control valve in the auxiliary pipe, and a check valve in the return pipe between the tank and the point of connection of the return and auxiliary 15 pipes.
2. In a system of water distribution, the combination with a tank having a discharge pipe leading to fixtures and having a return pipe leading from a point of hot water supply, of an auxiliary pipe connected at one 20

end to said return pipe and at its opposite end to said discharge pipe, a control valve 25 in said auxiliary pipe, a control valve in the discharge pipe, and a check valve in the return pipe between the tank and the point of connection of the return and auxiliary 30 pipes.

3. In a system of water distribution, the combination with a tank having a discharge pipe leading to fixtures, and a heating coil having a return pipe leading to the tank and having a supply pipe leading from the 35 tank to the coil, of an auxiliary pipe connecting the return pipe and the discharge pipe, means for controlling the flow through the discharge pipe and auxiliary pipe at will, and means for preventing the flow 40 through the return pipe except toward the tank.

JOHN A. WILLIAMS.
